UNITED STATES PATENT OFFICE

CHARLES J. BOYD, OF AMARILLO, TEXAS

AEROPLANE

Application filed November 3, 1928. Serial No. 316,973.

The present invention relates to an aero-⁵ plane and has for its prime object to provide wings which may be folded back in perpendicular form by unfastening a fixture of each wing and further in the provision of a strut that carries the weight of the wings when folding as well as assists other struts in flight.

Another very important object of the invention resides in the provision of the combination of the braces and struts so formed that the wings do not have to be removed from the aeroplane when folded back but certain joints are so placed as to admit of perfect action and movement in folding without the necessity of lifting the wings.

A further very important object of the invention resides in the provision of an aeroplane structure of this nature which is exceedingly simple, strong and durable, easy to manipulate, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of an aeroplane embodying the features of my invention,

Figure 2 is a front elevation thereof,

Figure 3 is a side elevation thereof,

Figure 4 is a side elevation thereof showing the wing section at the end of the first folding movement,

Figure 5 is a side elevation thereof showing the wings back,

Figure 6 is a detail view of the front fastening devices for the wing sections,

Figure 7 is a detail section through the rear hinge connection, and

Figure 8 is a sectional view showing one of the ball and socket connections for the struts.

Referring to the drawing in detail it will be seen that the numeral 5 denotes a fuselage

with a wing extending transversely across the forward portion thereof.

This wing includes a central section 6 permanently supported by suitable struts 7 and a pair of side foldable sections 8. The sections 8 are engaged with the sides of the section 6 by novel hinge connections A and novel releasable fasteners B. The hinge connection will be described first and particular attention is directed to Figure 7.

This hinge connection A comprises a plate 9 bolted as at 10 to the rear side portions of the central section 6 and a trunnion pin 11 projects from the plate 9. A sleeve 12 is rotatable on the pin 11 and is formed at its inner end with an outwardly directed annular flange 14.

A cap plate 15 has a flange portion 16 extending over the flange 14 for holding the sleeve in place and allowing the sleeve to rotate on the plate 11. The cap plate 15 is held in place by the bolts 10. A member 18 is provided with a pair of ears 19 straddling the sleeve 12 and hingedly connected therewith by means of a removable pin 20 which passes therethrough and through registering openings in the sleeve 12 and is held against accidental removal by a cotter pin 21 or in any other suitable manner. This member 18 is provided with a pair of spaced parallel arms 22 for straddling one of the wing spars of section 8.

There are two of these hinge connections one to each side of the rear portion of the section 6 and one connected to each of the rear of the inner side of the sections 8 so that the sections 8 may be swung from substantial horizontal position as shown in Figure 3 downwardly to a substantial vertical position as shown in Figure 4.

Struts 24 have ball and socket connections 25 with the fuselage and ball and socket connections 26 with the sections 8 so as to permit the swinging movement just described.

Particular attention is now directed to the fasteners B disclosed to advantage in Figure 6. Each fastener comprises a plate 27 with ears 28 projecting in one direction to straddle a wing spar 29 of section 6 and a pair of

apertured ears 30 projecting in the opposite direction.

A plate 31 is provided with ears 32 in one direction to straddle a wing spar 33 in section 8 and with an extension 34 in the opposite direction for disposal between the ears 30 and is provided with an opening so that a pin 35 may pass through the apertures of the ears 30 and through said opening in the extension 34.

10 Cotter pins 36 prevent the accidental removal of the pins 35. These pins 35, however, are adapted to be removed when the wing is to be folded whereas pins 20 are not removed except when the wing sections 8 are to be removed entirely from the fuselage. The fastening devices B are located between adjacent edges of the sections 6 and 8 and forwardly of the hinge connection A and the 15 fastening devices are unfastened so that the sections 8 may be swung to the position shown in Figure 4 and then swung to the position shown in Figure 5.

In swinging from the position shown in 20 Figure 3 to the position shown in Figure 4 the movement is accomplished by the rocking of the sleeves 12 on the pins 11, and the movement of the wing from the position shown in Figure 4 to the position shown in Figure 5 is 25 accomplished by the swinging of the members 8 on the pins 20.

Inverted V-shaped struts 40 have hinge connections 41 with the fuselage at their ends and at their apexes have ball and socket connections 42 with the forward end portions of the wing sections 8. The struts 24 and 40 may be provided with adjusting turnbuckles as is indicated at 43 in Figure 8 so that the lengths of the struts may be adjusted for 30 throwing up the sections 8 if this should be necessary.

The ball and socket connection 42 is unfastened when the wings are to be folded and the struts 40 allowed to swing downwardly 45 to the position shown in Figure 4 after which they are swung upwardly to the position shown in Figure 5 so that the aeroplane may be run into a comparatively compact space.

I do not claim to be the first in the art to 50 produce an aeroplane with foldable wings but my improvement resides more particularly in the provision of a foldable structure in the wings wherein it is not necessary to remove the wings from the fuselage in order to place 55 them in folded compact relation thereto.

The present embodiment of the invention has been disclosed in considerable detail merely for the purpose of exemplification since in actual practice it attains the features 60 of advantage enumerated as desirable in the statement of the invention and the above description.

It will be apparent that changes in the details of construction, and in the combination 65 and arrangement of parts may be resorted to

without departing from the spirit or scope of the invention as hereinafter claimed or sacrificing any of its advantages.

Having thus described my invention, what I claim as new is:

1. In an aeroplane, a fuselage, a wing structure across the fuselage including a central section and a pair of end sections, means for rigidly mounting the central section on the fuselage, universal hinge connections between the rear end of the inner sides of the end sections and the rear side edges of the central section and detachable connections between the forward ends of the inner side edges of the end sections and the forward side edges of the center section, struts having universal connections with the fuselage and with the end sections. 70

2. In an aeroplane, a fuselage, a wing structure across the fuselage including a central section and a pair of end sections, means for rigidly mounting the central section on the fuselage, universal hinge connections between the rear end of the inner sides of the end sections and the rear side edges of the central section and detachable connections between the forward ends of the inner side edges of the end sections and the forward side edges of the center section, struts having universal connections with the fuselage and with the end sections, a pair of struts for each side of the fuselage, one of said pairs being inverted V-shaped. 80

3. In an aeroplane, a fuselage, a wing structure across the fuselage including a central section and a pair of end sections, means for rigidly mounting the central section on the fuselage, universal hinge connections between the rear end of the inner sides of the end sections and the rear side edges of the central section and detachable connections between the forward ends of the inner side edges of the end sections and the forward side edges of the center section, a hinge connection including a plate secured to the center section and having a pin projecting therefrom, a sleeve rockable on the pin and having an inner flange directed outwardly, a cap plate on the first mentioned plate to hold the sleeve on the pin by engaging the flange thereof, and a member having a pair of ears straddling the sleeve, a pin projecting through openings in the ears and the sleeve to hinge the member on the sleeve, and ears projecting from the member for engagement with winch bars of the end sections. 95

4. In an aeroplane, a fuselage, a wing structure across the fuselage including a central section and a pair of end sections, means for rigidly mounting the central section on the fuselage, universal hinge connections between the rear end of the inner sides of the end sections and the rear side edges of the central section and detachable connections between the forward ends of the inner side 100

edges of the end sections and the forward side edges of the center section, a hinge connection including a plate secured to the center section and having a pin projecting therefrom, a sleeve rockable on the pin and having an inner flange directed outwardly, a cap plate on the first mentioned plate to hold the sleeve on the pin by engaging the flange thereof, and a member having a pair of ears straddling the sleeve, a pin projecting through openings in the ears and the sleeve to hinge the member on the sleeve, and ears projecting from the member for engagement with winch bars of the end sections, each fastener comprising a plate fixed to the center section and having spaced ears and a plate fixed to the respective end sections having a projection between the ears and a pin hingedly extending between the ears.

10   In testimony whereof I affix my signature.
20   CHARLES J. BOYD.
